Patented Dec. 22, 1959

186,884

GIRDLE

William J. Dorsey, Dover, Del., assignor to International Latex Corporation, Dover, Del., a corporation of Delaware

Application May 2, 1958, Serial No. 50,717

Term of patent 14 years

(Cl. D20--2)

Fig. 1.

Fig. 2.

The dominant feature of the design resides in the portion shown in full lines on the drawings.

The decorative effect is formed by depressing the background.

I claim:

The ornamental design for a girdle, substantially as shown and described.
